178,408

DESK OR SIMILAR ARTICLE

Cloyd T. Konkle, Montoursville, Pa.

Application September 2, 1955, Serial No. 37,771

Term of patent 14 years

(Cl. D33—11)

FIG. 1

FIG. 2

Fig. 1 is a perspective view of a desk showing my new design;

Fig. 2 is a front elevational view thereof with the top element omitted for convenience of illustration; and

Fig. 3 is a side elevational view thereof as shown in Fig. 2.

The dominant features of my design reside in the portions shown in full lines.

I claim:

The ornamental design for a desk or similar article, as shown and described.
